UNITED STATES PATENT OFFICE.

HENRY P. MERRIAM, OF NEW YORK, N. Y.

CONTROLLING MECHANISM FOR LOOMS.

1,000,746.

Specification of Letters Patent. Patented Aug. 15, 1911.

Application filed March 28, 1911. Serial No. 617,491.

To all whom it may concern:

Be it known that I, HENRY P. MERRIAM, a citizen of the United States, and a resident of the borough of Manhattan, city, county, and State of New York, have invented certain new and useful Improvements in Controlling Mechanism for Looms, of which the following is a specification.

In my Patent No. 981,299 granted to me January 10th, 1911, I have covered a controlling mechanism for looms comprising essentially a fluid pressure actuated controlling device and means controlled by the presence or absence of weft in the active shuttle for regulating the pressure applied to said controlling device. In the practical development of the mechanism covered by said patent, I have produced certain improvements in the valved contact member which not only simplify and cheapen the construction, but increase the sensitiveness and accuracy of the mechanism. These improvements constitute the subject of the present application.

In the improved form of pneumatic filling detecting device, the tubular weft contacting member is provided with a pressure controlling valve arranged at the contact end of said member so as to reduce to a minimum the clearance space between the valve and the filling carrier and provide a more direct communication between the weft contacting member and the fluid pressure actuated controlling device. With this improved structure, the controlling valve is held open all the time that the contact member is in contact with the filling carrier and is partaking of its backward and forward motions, so that I am able to reduce to a minimum the interval of contact of said member with the filling carrier. Thus the movement of the contact member is the more completely reduced to that part of the stroke of the lay which occurs when its driving crank is passing the center of the driving shaft and is consequently moving the least rapidly. With the small mass of the valved contact member together with the small amount of movement necessary to effect the operation of the fluid pressure actuated controlling device and this movement occurring at the end of the stroke of the lay, the contact member is made effective with a lightness of touch on the filling which in no way disturbs the windings of the filling on the cop or bobbin, which otherwise might be broken

down and disarranged, and thereby cause the breakage of the filling from the tangling of the thread. The location of the controlling valve at the contact end of the weft contacting member also facilitates the employment of a simpler form of valve which is more reliable than the form shown in the mechanism of my above named patent.

In addition to the above recited advantages of my improved form of weft contacting member in a general sense, there are other advantages incident to specific forms of the mechanism hereinafter referred to.

In order that my invention may be fully understood, I will first describe the same with reference to the accompanying drawings, and afterward point out the novelty more particularly in the annexed claims.

In said drawings: Figure 1 is a detail plan view of part of a loom having my improved pneumatic controlling mechanism applied thereto. Fig. 2 is an enlarged plan view of the improved pneumatic weft contacting member. Fig. 3 is a vertical longitudinal sectional view of the same. Fig. 4 is an end view of the contact end of said member. Fig. 5 is a view similar to Fig. 2 of a slight modification. Fig. 6 is a view similar to Fig. 3 of the form shown in Fig. 5. Fig. 7 is a view similar to Fig. 4 of the same form. Fig. 8 is a detail sectional plan view of a further modification showing a form of the controlling device particularly applicable to the cop winding filling. Fig. 9 is a detail vertical longitudinal sectional view of parts of the same. Fig. 10 is a detail longitudinal sectional view of the valved contact member of the form of device shown in Fig. 8. Fig. 11 is a face view of the contact members shown in Fig. 10. Fig. 12 is a detail sectional view of a further modification showing a form of device particularly applicable for use with a bobbin having a ribbed conoidal winding head. Fig. 13 is a detail view of the form of device shown in Fig. 12. Figs. 14, 15, 16, 17 and 18 are detail views illustrating further modifications in the form of the weft contact member of the improved controlling device.

It will be understood that the improved weft contact device hereinafter described is intended to be employed in connection with a fluid pressure actuated loom controlling device such as set forth in my above named Patent No. 981,299. In Fig. 1 of the draw-

ings I have shown the essential parts of such a mechanism. In this figure of the drawings, 1 represents the breast beam, 2 the lay bar, and 3 the shuttle box at the left hand end of the lay bar. 5 represents a shuttle in the shuttle box 3, and 6 the weft bobbin mounted in the shuttle in the usual way. These parts are all of usual construction with the exception that the front wall of 10 the shuttle box 3 has an opening 4 cut through it and the front wall of the shuttle 5 has an opening 5^a cut through it which is designed to register with the opening 4 of the shuttle box when the shuttle is in 15 proper position therein for the reception of the weft detecting device in the manner hereinafter explained. 10 is the ordinary shipper bar by which the loom is thrown into and out of operation. This shipper bar 10 is indicated only in section in Fig. 1 of the drawings but it will be understood that it is mounted in the usual manner and connected up with the belt shifting devices. This shipper bar 10 is retained in position for holding the loom in operation by the shoulder 11 formed in the plate of the breast beam 1, and when the shipper bar is disengaged from said shoulder, its spring moves it to the left of Fig. 1 in the slot 12 20 in a manner well understood. 13 is a lever pivoted at 16 upon the breast beam 1 in position to engage the front of the shipper bar 10 at one end and to be engaged by the adjustable controlling and operating slide 17 25 mounted upon the breast beam in the usual manner and carrying at its forward end the usual weft detecting fork 18 which is operated by the weft hammer indicated at 20. This throw out mechanism under the control 30 of the weft detecting fork 18 is of common construction. Arranged alongside of the slide 17 in suitable guideways 23 upon the breast beam 1 is a second controlling slide 26 which is designed to be connected in 35 any suitable manner with any appropriate form of weft replenishing mechanism. In the drawings, I have shown part of a vertical lever 30 connected with the controlling slide 26 through a link 31. The slide 26 has 40 pivotally mounted upon it a controlled dog or detent 28 which is adapted to be engaged by the weft hammer 20 for operating said slide and throwing into action the mechanism connected therewith. The weft hammer 20 is formed with a U-shaped upper end as in my above named patent, one arm being arranged to engage the dog of the weft detecting fork 18, while the other is arranged to engage the dog 28 of the slide 26. The 45 dog or detent 28 is provided with an angular arm 28^a which projects over the rearwardly presented arm 35 of a controlling lever 36 mounted upon a pivot rod 37 supported at its ends in the adjustable bearings 38 seated in brackets 39. A torsion spring 40 is coiled 50 upon the pivot rod 37 with one end in engagement with the controlling lever 36 and the other end in engagement with an adjustable disk 41 pivoted upon one of the bearings 38 and formed with a series of holes 55 or openings 42 into which the retaining pin 43 is designed to engage for holding the torsion spring 40 adjusted to the desired tension. The retaining pin 43 is slidingly mounted in one of the brackets 39 so that it can readily be moved into and out of engagement with the holes or openings 42 of adjustable disk 41. This controlling lever 36 extends diametrically across the casing of a controlling diaphragm which constitutes 60 an element which I have heretofore referred to as a "pressure operated device" for controlling the above described dog or detent upon the slide 26. A cylindrical diaphragm casing 45 is suitably mounted upon the breast beam of the loom alongside of the guideway 23. Mounted within the casing 45 in the manner explained in my above named patent, is an expandible diaphragm (not shown) upon which the controlling lever 36 rests, and by which said lever is raised and lowered for controlling the position of the dog 28. This action is fully explained in my above named patent. Leading from the diaphragm chamber 45 beneath the diaphragm is a port or passage indicated at 55 which communicates with a coupling 56. An air supply pipe 57 connects the coupling 56 with an air pump or other suitable source of air under pressure. A throttling screw 100 valve 58 is threaded into the coupling 56 to control the size of the air passage. A branch pipe 59 communicating with the coupling 56 has connected with it a short section of flexible hose or pipe 60 which 105 communicates at its opposite end with a nipple 61 of the tubular weft detecting device to which my present invention relates. Secured to the end of the breast beam 1 by means of screws 66 is a rearwardly projecting guide bracket 65 formed with horizontal guideways 67 indicated by dotted lines in Fig. 1. Mounted in the guideways 67 is a horizontal reciprocating weft detecting member 70 provided with a forwardly projecting 115 rod 73 which extends through a guide opening formed in the forward end of guide bracket 65. An expansion spring 76 surrounds the rod 73 and is confined between the end wall of bracket 65 and the head of 120 the rod which is connected with the member 70. The expansion spring tends to hold the member 70 in its rearmost or inner position with a yielding pressure so that the member 70 can move forwardly when engaged by the 125 filling or filling carrier in the shuttle. The weft detecting member 70 carrying the nipple 61 is formed with a longitudinal bore or passageway 81 leading from the nipple 61 and communicating freely with the bore or 130

opening of the self-adjusting contact head 110. This self-adjusting head 110 is shaped to fit snugly in the crescent-shaped opening formed in the inner end of the sliding member 70 and is free to adjust itself in a horizontal plane upon the member 70. The means for adjustably connecting the head 110 upon the member 70 are fully explained in my above named Patent No. 981,299 and 10 form no part of the present invention. The contact head 110 is formed with a longitudinal bore or passageway 111 extending through it and with a weft engaging face 112 formed with an internal shallow recess 113 with which the passageway 111 communicates. A circular valve seat 114 is formed in the passageway 111 adjacent to its juncture with the recess 113. A ball valve 115 is fitted upon the valve seat 114 and 20 yieldingly held in place thereon by means of a short expansion spring 116 located in the passageway 111 and confined in working position by a small pin 117 extending across passageway 111 and properly seated in the 25 side walls of the head 110. The location of the valve seat 114 and the size of the ball valve 115 are such that the ball will project slightly beyond the contact face 112 of the head 110 so that when said head is 30 moved into engagement with the weft carrier or the filling wound thereon, the ball will be unseated to open up communication between the shallow recess 113 and the passageway 111. With this form of the 35 device, it will be understood particularly with reference to my above named Patent No. 981,299, that in the operation of the loom equipped with my improved controlling mechanism, the supply of air under pressure 40 beneath the controlling diaphragm retains the controlled dog 28 out of the path of the weft hammer. This air is maintained beneath the diaphragm by the valve 115 in the contact head 110 of the weft detecting member. Upon each alternate movement of the 45 lay toward the breast beam, the shuttle comes into position in the shuttle box at the left hand end of the lay and as the shuttle box reaches the limit of its movement toward the breast beam, the contact head 110 is presented through the openings 4 and 5 of the shuttle box and shuttle and brought 50 into engagement with the weft wound, upon the bobbin or other form of weft carrier in the shuttle. This engagement unseats the ball valve 115 and opens up communication 55 between the recess 113 and channel 111 which is in free communication with the diaphragm chamber. If, however, there is sufficient length of weft upon the bobbin at the 60 moment of said engagement, the recessed face of the head 110 will be completely closed by the yielding weft being pressed against said recessed face, the head 110 automatically adjusting itself upon the member 70 to fit 65 snugly against the weft in such engagement and thereby preventing the escape of the air under pressure from the recess 113. In this manner the wound weft prevents the material reduction in the pressure beneath 70 the diaphragm so that the controlled dog will be retained out of the path of the weft hammer. The engagement of the wound weft with the detecting device occurs during 75 the completion of the forward movement of the lay toward the breast beam, the member 70 yielding slightly to permit such movement. This operation continues for each alternate movement of the lay toward the breast beam. As the weft is used up from 80 the active shuttle, the self-adjusting head 110 of the detecting device automatically corrects its position for each engagement so as to close the escape for compressed air so long as sufficient weft remains in the shuttle for a succeeding to and fro flight. When the weft is nearly exhausted and the grooved winding head of the bobbin becomes partly uncovered, there will not be sufficient weft 85 left to close the recessed face of the head 110, so that upon the unseating of the valve 115, the air under pressure beneath the diaphragm and in the channels leading therefrom to the valve will escape and the reduced pressure will lower the diaphragm 90 sufficiently to permit the controlled dog to fall into the path of the weft hammer, which upon its next succeeding stroke, will engage the depressed dog and operate the slide for 95 stopping the loom or actuating the weft replenishing mechanism. 100

In Figs. 5, 6 and 7 of the drawings, I show a slight modification of the pneumatic weft detecting member in which a different form of valve is employed. The slide member 70 is provided with the self-adjusting head 110 as in the form above described. The contact face 112 of head 110 is formed with a recess 113 of slightly different shape, with lateral extensions or notches 113^b to 110 afford a slightly increased escape for the air when the relief valve is opened. In place of the ball valve above described, this form of the device includes a conical valve 120 formed on a short hollow guide cylinder 121 115 which fits in the channel 111 of the head. Guide slots 122 are formed in the cylinder 121 and a transverse pin 123 seated in the side walls of the head 110 extends transversely of the channel 111 and engages the slots 122. A spring 124 is mounted in the hollow of cylinder 121 and confined by the pin 123 so as to hold the valve to its seat. The valve member is of slightly reduced 120 diameter adjacent to the valve seat as indicated at 125 in Fig. 6 and has two parallel grooves 126 drilled transversely through its outer edge in said reduced portion to form air escape channels. In drilling these 125 grooves 126, air escape ports 127 are formed 130

in the side walls of the valve member. The valve seat 114^a in the end of the channel 111^a is of conical shape to receive the conical end of the valve. Projecting centrally from the end of the valve is a small pin or stud 128 which is flattened and sharpened slightly at its outer end to enable it to penetrate between the windings of the weft upon the weft carrier, the position of said flattened pin being such that its longer transverse axis will lie parallel with the windings of the weft upon the carrier. This flattened pin projects beyond the contact face of the head 119 to a very slight degree. In the operation of this modified form of filling detecting member, it will be understood that normally the pin projection 127 of the valve will embed itself between the windings of the weft or filling under the pressure of the valve closing spring 124 so that the valve will not be opened until such time as the weft or filling has nearly reached the point of exhaustion. At this point the more resisting core of the filling carrier will press against the end of the valve pin and unseat the valve more and more as the filling upon the carrier is reduced. Finally a time is reached when there is so little filling left upon the carrier, that when the valve is opened as explained, the air will escape from the recessed face of the contact head and the diaphragm will be lowered sufficiently to allow the operation of the controlled mechanism.

In Figs. 8, 9, 10 and 11 of the drawings, I show a further modification of my invention designed particularly for use with cop wound filling. It will be understood that in winding the weft or filling upon a small cop or quill such as indicated at 130 in Fig. 8 of the drawings, the quill is supported upon a skewer and the weft or filling wound thereon by first winding several layers upon the quill and then gradually extending the winding out over the skewer. In applying my invention to this form of filling winding, it is desirable to not only limit the action of the weft detecting device to the zone of the small quill which is the base or support for the wound filling, but also to prevent the feeling or detecting operation of the device until the main body of the filling has become exhausted. These results are accomplished by the form of my invention shown in Figs. 8 to 11. In this form of the device, I provide a different supporting bracket for the filling detecting member, which bracket comprises top and bottom plates of the shape shown at 140 having lateral guide flanges 140^a and 140^b. These plates 140 are secured together upon the breast beam of the loom with a spacing plate 141 separating them, said spacing plate 141 being of the same general outline as the top and bottom plates 140, but being

cut out on its inner edge upon the dotted line 142 to form with the top and bottom plates a guide channel for the movable slide of the detecting device. 143 is the rectangular slide frame of the yielding device, which rests between the arms 140^a of the top and bottom plates 140 and slides upon the face 142 of spacing plate 141. A guide rod 144 is formed with a bifurcated outer end 144^a which embraces the arms 140^a of top and bottom plates 140 and the similar arm of the spacing plate 141, thereby supporting the rod 144 in its operative position. This rod 144 is formed with an axial slot 146 in which operates the inner end of the slide member 143. The inner end of the rod 144 is shouldered as indicated at 147 to fit snugly upon the arms 140^b of the top and bottom plates to effect the mutual support and relative location of the rod 144 and arms 140^b. An expansion spring 148 surrounds the rod 144 and is confined at its ends between the arms 140^b and the slide member 143 with the result that the member 143 and parts carried thereby are yieldingly held in operative relation to the filling carrier in the shuttle. The sliding member 143 has rigidly secured to it a tube of metal 150 as shown in Fig. 8. This metal tube 150 extends longitudinally of the slide member 143 and is of the same length thereof. Freely mounted in the end of the tube 150 is an automatically adjustable contact head 155 formed with spheroidal side walls which fit snugly in the bore of the tube 150. The shape of this head 155 enables it to move universally in its supporting tube 150. The head 155 is of hollow formation as shown in Fig. 10 and the inner nipple extension 156 is seated in the end of a short section of rubber pipe 157 which extends into the metal tube 150 and is confined in proper position by the internal flange 158 at the forward end of the tube. This rubber tube 157 is designed to be attached to the branch pipe 56^a of the coupling 56 so that the adjustable head 155 will be in open communication with the diaphragm chamber illustrated in Fig. 1 of the drawings. The described mounting of the head 155 with only the rubber tube 157 to hold it in place will enable said head to move into the tube 150 by a slight longitudinal compression of tube 157 and also to change its angular relation upon the end of the tube 150 to enable it to accurately adjust its contact face to the surface of the filling or filling carrier. The contact face of the head 155 is formed with shallow grooves or recesses 155^a extending across it as indicated in Fig. 11. These grooves communicate with the central opening 155^b in the contact face. Mounted in the head 155 is a valve 160 consisting of a tightly wound spiral spring soldered or otherwise

secured at 161 in the recessed inner wall of the contact head and soldered or otherwise attached at 162 to the headed end of the controlling pin 163 which extends longitudinally of the head 155 and projects to a limited extent beyond the contact face of the head 155. It will be understood that in the form of valve shown in Fig. 10, the spiral spring constitutes the valve as well as the valve spring since the convolutions of the spring fit snugly together and form an air-tight valve. The valve is operated by forcing the pin 163 inwardly which opens the convolutions of the spring valve more or less to allow air to pass from the channel of the head 155 into the bore of the spring valve and out through the central opening 155^b to the recessed face of the head.

20 In the operation of the form of the device just described, it will be understood that, so long as the filling upon the cop or quill retains approximately its original shape at its base as indicated in Fig. 8 of the drawings, 25 the body of the filling will engage the inner end of the sliding member 145 every time the shuttle moves toward the detecting device, and that the detecting device will yield under this action without having any effect 30 upon the pneumatic control. In this normal engagement of the filling with the detecting device, it will be observed that the universally adjustable head 155 is held out of 35 engagement with the filling because of the contour of the wound filling. This operation continues until the greater part of the filling is removed from the cop or quill. When the filling is reduced to the several layers immediately surrounding the quill, it 40 will be observed that there will no longer be any filling in the path of the slide member 145, but that the valved head 155 will be brought directly into contact with the wound filling. For the first few engagements of the filling with the head 155, the slightly projecting valve pin 163 will embed itself in the filling and the valve will not be opened. As the operation progresses, however, the end of the pin will come in contact 50 with the harder surface of the cop or quill with the result that the relief valve 160 will be opened to a greater or less extent. If sufficient filling still remains upon the quill, the recessed face of the head 155 will be covered sufficiently to prevent the escape of air from the head. The moment, however, that the filling has reached such a degree of exhaustion that the escape of air from the recessed face of the head 155 is no longer prevented, it will be understood that the opening of the valve will permit a sufficient escape of air to lower the controlling diaphragm to cause the automatic mechanism to operate. In the varying operations of 65 this form of device, it will be understood

that the contact head 155 automatically adjusts its contact face to the surface of the filling upon the quill, so as to effect a more uniform bearing upon the filling when the valve comes into operation with the result 70 that the air released by the valve is trapped in the face of the head while there is sufficient filling left upon the quill for this purpose. This automatic adjustment of the contact head is of great advantage by reason 75 of the fact that, in addition to the variations in the compressibility of the filling material at the several points immediately under the surface of contact of the head with the filling, due to the progressive unwinding of the 80 filling and the lack of exactness of longitudinal positioning of the shuttle in its box from stroke to stroke, there is also a lack of exactness in the vertical positioning of the shuttle, so that the axis of the shuttle is 85 not always a fixed distance above the shuttle race.

In Figs. 12 and 13 I show a further modification embodying the same form of spring valve shown in Fig. 10, but providing means for more accurately detecting the proper point of exhaustion of the filling upon the form of bobbin provided with the grooved tapered winding head or base. In this form of detecting device a tubular member of any suitable general shape, such as indicated at 90 165, is designed to be yieldingly mounted upon the breast beam of the loom in some suitable manner, such for instance as described in connection with Fig. 1 of the 95 drawings. This tubular member 165 has a central bore or channel 166 extending through it and a shouldered outlet 167 in which is mounted a spring valve 168 of the construction above described in connection 100 with Fig. 10 of the drawings. A valve pin 169 projects from the valve 168 a trifle beyond the face of the tubular member 165. The wall of the tubular member 165 is bored 105 longitudinally from its contact face parallel with its axis to form guideways 170 in which are mounted the legs of a yoke-shaped valve-operating member 171. This member 171 extends diametrically across the contact face of tubular member 165 in engagement 110 with the projecting end of the valve pin 169, so that upon depressing the member 171 the valve will be forced open. The end of the tubular member 165 is reduced slightly as indicated at 175 to receive a soft rubber 115 sleeve 176 which by reason of its elasticity, is drawn closely around the contact face of tubular member 165 and into engagement with the yoke member 171 for confining the latter in place. Figs. 12 and 13 clearly show 120 this arrangement. In the operation of this last described form of the device, it will be understood that the fluid pressure actuated controlling device will be operated only at 125 such time, upon the opening of the valve 130

168, that the filling remaining upon the bobbin is insufficient to check the escape of air from the cupped contact face outlined by the edge of the rubber sleeve 176. The 5 staple or yoke-shaped valve operating member 171 will open the valve 168 when it engages one or more of the circular ribs upon the bobbin or when the filling upon the bobbin affords sufficient resistance to the engagement to overcome the strength of the 10 spring of the valve 168. The rubber sleeve 176 is capable of being pressed only part-way into the grooves of the bobbin so that in the absence of filling upon the bobbin, the 15 escape of air is not checked by the sleeve. With this arrangement, I am able to reduce the quantity of filling left upon the bobbin to a minimum, for the reason that so long as there is sufficient filling wound in the 20 grooves of the bobbin to form a tight contact with the edge of the rubber sleeve, the air under pressure will be held from escape even though the valve is opened by the engagement of member 171 with the projecting 25 ribs of the bobbin. This form of device also has the advantage of more accurately determining the proper point of actuating the 30 automatic throw-out or shuttle changing mechanism, because of its operation by one or more of the projecting shoulders or ribs, whereas in the form of device dependent upon the engagement of the single projecting pin of the valve stem or rod, the variations in position of the shuttle in the shuttle 35 box would produce lack of uniformity in the result.

In Figs. 14, 15 and 16, I have shown another form of detecting device employing a soft rubber contact head. In this form the 40 tubular slide member indicated at 180 has seated in its end a soft rubber contact head 181 formed with an internal cavity 182 and the centrally separated rubber valve lips 183 which normally close the opening 45 through the contact head. Seated in a suitable recess 184 in the contact face of the head 181 is an open spiral spring 185 which rests just above the normally closed valve lips 183 as shown in the drawings. The pressure 50 of the coiled spring 185 against an unyielding part or parts of the bobbin will force the spring inwardly and separate the valve lips 183 to open up communication from the tubular member 180 to the recessed 55 face of the head 181. At such times the air under pressure will be allowed to escape through the grooves of the bobbin, unless sufficient filling remains upon the bobbin to make an air-retaining closure with the 60 yielding walls of the contact head 181. It will be understood that the member 180 is designed to be mounted upon a suitable slide such for instance as described in connection with Fig. 1 of the drawings.

In Figs. 17 and 18, I have shown the same

form of device illustrated in Figs. 14, 15 and 16, slightly modified by adding to the yielding rubber contact head 181, suitable corrugated or grooved wearing strips 186 which are of some hard and unyielding material. In this form of the device, the air is not so completely trapped between the walls of the contact head and the bobbin and filling.

The advantages resulting from the 75 mounting of the relief valve in the contact end of the weft detecting member are first: the reduction to a minimum of the clearance space between the valve and weft carrier, with the result that there is no material loss 80 of compressed air while the loom is operating normally; second: the provision of a more direct communication from the diaphragm to the valve contact end of the weft detecting member; and third: the simplification of the structure, which results in increased accuracy and wearing qualities.

In illustrating the application of my present invention to the control of looms, I have shown and described it as applied to 90 a pneumatic loom controlling mechanism such as covered by my prior Patent No. 981,299. I would have it understood that I do not intend to limit my present invention to this specific form of controlling 95 mechanism, but intend in my claims to cover a pneumatic pressure actuated controlling device for looms in the broadest possible sense. This controlling mechanism may be variously constructed both as 100 to the arrangement of parts of the pressure actuated device and as to the arrangement of the detecting device with reference to the shuttle. For instance, in place of the arrangement shown, in which the detecting device is presented through registering openings in the shuttle box and shuttle for 105 engaging the weft carrier or weft wound thereon upon one side, it will be perfectly clear that the principle of my invention can 110 be readily carried out by other arrangements, by which the detecting device can be brought into contact with the weft carrier or weft wound thereon at any other side.

What I claim is:

1. In a controlling mechanism for looms, the combination of a pneumatic weft detecting device and a pressure relief valve in the contact end of said device, with a pressure actuated controlling device in communication with said detecting device.
2. In a controlling mechanism for looms, the combination of a pneumatic weft detecting device, and a pressure relief valve 125 mounted in the contact end of said device and adapted to be operated by the engagement of the weft carrier or the weft wound thereon, with a pressure actuated controlling device in communication with said de- 130

tecting device, and a source of air pressure communicating with said controlling device.

3. In a controlling mechanism for looms, the combination of a yieldingly mounted pneumatic weft detecting device, and a normally closed pressure relief valve mounted in the contact end of said device, with a pressure actuated controlling device in communication with said detecting device, and a source of air pressure communicating with said controlling device.

4. In a controlling mechanism for looms, the combination of a pneumatic weft detecting device, an automatically adjustable weft contacting head mounted upon said detecting device, and a pressure relief valve mounted in the contact end of said head, with a pressure actuated controlling device in communication with said head.

5. In a controlling mechanism for looms, the combination of a yieldingly mounted pneumatic weft detecting device, an automatically adjustable weft contacting head mounted upon said detecting device, and a pressure relief valve mounted in the contact end of said head and adapted to be operated by contact with the weft carrier or weft wound thereon, with a pressure actuated controlling device in communication with said head.

6. In a controlling mechanism for looms, the combination of a yieldingly mounted pneumatic weft detecting device, a self-adjusting weft contacting head movably mounted upon said detecting device, and a normally closed pressure relief valve mounted in the contact end of said head, with a pressure actuated controlling device in communication with said detecting device.

7. In a controlling mechanism for looms, the combination of a pneumatic weft detecting device, a weft contacting head thereon formed with a recessed contact face, and a pressure relief valve mounted in the recessed contact end of said head, with a pressure actuated controlling device in communication with said detecting device.

8. In a controlling mechanism for looms, the combination of a pneumatic weft detecting device having a tubular weft contacting head, and a pressure relief valve mounted in the contact end of said tubular head, with a pressure actuated controlling device communicating with said detecting device.

9. In a controlling mechanism for looms, the combination of a pneumatic weft detecting device having a tubular weft contacting member, and a pressure relief valve mounted in the contact end of said member, and having a part projecting from it beyond the contact face of said member in position to be engaged and operated by the weft carrier or the weft wound thereon, with a

pressure actuated controlling device communicating with said weft detecting device.

10. In a controlling mechanism for looms, the combination of a weft detecting device, a weft contacting head carried thereby, a normally closed pressure relief valve mounted in the contact end of said head, and a valve opening member projecting beyond the contact face of said head, with a pressure actuated controlling device in communication with said head.

11. In a controlling mechanism for looms, the combination of a weft detecting device having a tubular weft contacting head, and a normally closed spring actuated pressure relief valve mounted in said head, with a pressure actuated controlling device in communication with said contacting head.

12. In a controlling mechanism for looms, the combination of a weft detecting device having a tubular weft contacting head, a normally closed spring actuated pressure relief valve mounted in said head and a valve stem attached to and projecting from said valve to a point slightly beyond the contact face of said head, with a pressure actuated controlling device in communication with said contacting head.

13. In a controlling mechanism for looms, the combination of a pneumatic weft detecting device having a tubular weft contacting head, a tightly wound spiral spring secured in said tubular head and constituting a pressure relief valve, and means for operating said valve, with a pressure actuated controlling device communicating with said head.

14. In a controlling mechanism for looms, the combination of a pneumatic weft detecting device having a tubular weft contacting head, a tightly wound spiral spring of tubular form having an open outer end in free communication with the outlet opening of said head and projecting into the cavity of the head and formed with a closed inner end and constituting a pressure relief valve, and means for operating said valve, with a pressure actuated controlling device communicating with said head.

15. In a controlling mechanism for looms, the combination of a pneumatic weft detecting device having a tubular weft contacting head, a tightly wound spiral spring of tubular form having an open outer end in free communication with the outlet opening of said head and projecting into the cavity of the head and formed with a closed inner end and constituting a pressure relief valve, a valve stem attached to the closed inner end of said spiral spring valve and extending therefrom to a point slightly beyond the contact face of said head, with a pressure actuated controlling device communicating with said head.

16. In a controlling mechanism for looms,

- 8
 the combination of a pneumatic weft detecting device having a tubular weft contacting head, a normally closed pressure relief valve mounted in the contact end of said head, and a valve stem projecting from said valve to a point slightly beyond the contact face of said head, with a pressure actuated controlling device communicating with said detecting device.
- 10 17. In a controlling mechanism for looms, the combination of a pneumatic weft detecting device having a tubular weft contacting head, a normally closed pressure relief valve mounted in the contact end of said head, and a valve stem projecting from said valve to a point slightly beyond the contact face of said head, and furnished with a flattened outer end having its longer axis lying parallel with the thread wound upon the weft carrier, with a pressure actuated controlling device communicating with said detecting device.
- 15 18. In a controlling mechanism for looms, the combination of a weft detecting member adapted to engage the body of weft wound upon a weft carrier in the active shuttle, a pneumatic weft detecting and contacting head mounted at one side of said detecting device in position to engage the weft wound upon the base of the weft carrier, and a pressure relief valve mounted in said head, with a pressure actuated controlling device communicating with said head.
- 20 19. In a controlling mechanism for looms, the combination of a slide member adapted to contact with the body of the weft wound upon the weft carrier, a pneumatic tubular weft contacting head mounted upon said slide member in position to be engaged by the weft wound upon the base of the weft carrier and an automatic pressure relief valve in said head, with a pressure actuated controlling device communicating with said head.
- 25 20. In a controlling mechanism for looms, the combination of a slide member adapted to contact with the body of the weft wound upon the weft carrier, a tubular member mounted upon said slide member, a pneumatic weft contacting head loosely mounted in said tubular member, an elastic pipe secured in said tubular member and attached to said head to yieldingly support it in operative position, an automatic pressure relief valve mounted in said head, and a pressure actuated controlling device in communication with said elastic pipe.
- 30 21. In a controlling mechanism for looms, the combination of a slide member adapted to contact with the body of the weft wound upon the weft carrier, a tubular member mounted upon said slide member, a pneumatic weft contacting head of spheroidal shape fitting loosely in said tubular member, an elastic pipe secured in said tubular member and attached to said head to yieldingly support it in operative position, an automatic pressure relief valve mounted in said head, and a pressure actuated controlling device in communication with said elastic pipe.
- 35 22. In a controlling mechanism for looms, the combination of a yieldingly mounted slide member adapted to contact with the body of the weft wound upon the weft carrier, a tubular member mounted upon one side of said slide member, a pneumatic weft contacting head loosely mounted in said tubular member with its contact face in approximately the same plane as the contact face of said slide member, an elastic pipe secured in said tubular member and attached to said head to yieldingly support it in operative position, an automatic pressure relief valve mounted in said head, and a pressure actuated controlling device in communication with said elastic pipe.
